SOLOMON S. MOYER, OF ALLENTOWN, PENNSYLVANIA.

Letters Patent No. 100,786, dated March 15, 1870.

IMPROVEMENT IN SIPHONS.

The Schedule referred to in these Letters Patent and making part of the same.

I, SOLOMON S. MOYER, of Allentown, in the county of Lehigh, and State of Pennsylvania, have invented a new and useful Improvement in Siphons for transporting Water and other Fluids, of which the following is a specification.

The nature of my invention consists in the combination of a vertical tube and faucet with the siphon-pipe, in such a manner as to arrest or regulate the flow of water through the siphon.

To enable others skilled in the art to make and use my invention, I will proceed to describe its construction and operation.

The drawing represents a vertical section through the improved siphon A and the reservoir B, from which water flows into the receiving end 1.

I imbed the pipe A in the ground beneath the surface, of sufficient depth to protect it from the frost, extending it over any number of hills C that may be required to reach the point to which the water has to be transported.

The bend at the point 2 I make lower than the receiving end 1, to produce suction.

The pipe at the point 3 is higher than the receiving end, and if extended no further would be merely a common siphon, and the water would be retained should the supply be cut off. But if it should be extended so as to have its discharging end as represented, lower than the receiving end, the water would still run out after it ceased to run in at the receiving end, and a suction would be produced whereby the pipe would be emptied of its contents.

In order to retain the water in the siphon, to provide for any contingency which might arise to prevent the supply of water or other fluid to be transported, I connect a vertical tube, D, with the pipe A at the point 3, which, as has been said, is higher than the receiving end of the pipe. This tube is open at its

upper end, to provide for a column of air to press upon water in the pipe A at that point. Then, if the water should at any time cease to flow into the receiving end, although it will run out of the discharging end beyond the vertical tube D, the pressure of the column of air in the tube upon the water at this point counteracts the suction, whereby the water is retained in the siphon.

I provide the tube D with a faucet, E, for regulating the discharge of water from the pipe A.

This is effected by turning the key F so as to regulate the area of air bearing upon the water at the point 3, and thus allowing the water to press forward with more or less force, so as to be discharged in sufficient quantity in a given time to suit the demand.

It must readily appear that when a siphon has its discharging end prolonged, as represented in the drawing, that without the device just described the siphon would be emptied of its contents when the supply should be cut off at its receiving end, and much loss of time and expense would be incurred in setting it to work again, especially if the pipe A should be of considerable length.

What I claim as new, and desire to secure by Letters Patent, is—

The combination of the vertical tube D and faucet E with the pipe A, the said parts being constructed and arranged in relation to each other substantially in the manner and for the purpose set forth.

In testimony that the above is my invention I have hereunto set my hand and affixed my seal, this 18th day of December, 1869.

SOLOMON S. MOYER. [L. S.]
